METHOD AND APPARATUS FOR CRACKING
HYDROCARBON OILSRobert A. Findlay, Bartlesville, Okla., assignor to
Phillips Petroleum Company, a corporation of
Delaware

Application November 13, 1950, Serial No. 195,416

11 Claims. (Cl. 196—55)

1

This invention relates to the conversion of hydrocarbon oils. In one of its more specific aspects it relates to a method for cracking heavy residual oils at high temperatures. In another of its more specific aspects it relates to an improved apparatus for cracking heavy residual oils at high temperatures.

Heavy residual oils have long posed a considerable problem in the petroleum industry. Although refining techniques of the petroleum industry have improved greatly during the past several years, heavy residual oils have been of little or no value because of the very great tendency of such materials to form and deposit coke, tar, or other carbonaceous deposits in refining equipment. As the demand for petroleum products has increased, that demand has placed a greater burden upon the natural resources of the world and has focused attention more directly upon what heretofore had been deemed waste materials. Heavy residual oils have been very closely akin to waste materials, and it is believed, therefore, that any process which aids in the utilization of such materials is of very great importance.

Many processes have been set forth in the petroleum art by which it has been proposed to crack heavy residual oils to provide normally lighter materials such as hydrogen and hydrocarbons and gasoline stocks. As pointed out above, however, the tendency for such materials to form carbonaceous deposits has made such processes relatively uneconomical. I have devised a process and an apparatus whereby the tendency of such heavy residual oils to form tarry and carbonaceous materials is utilized to a considerable extent so as to actually obtain benefit therefrom. Recent developments in the cracking of heavy residual oils have led to the utilization of the so-called pebble heater apparatus for converting such oils at high temperatures.

So-called pebble heater apparatus utilize a gravitating mass of solid heat exchange material, which mass is heated to a high temperature by passing hot gas therethrough in a first direct heat exchange step and is then caused to contact reactant materials, furnishing heat thereto in a second direct heat exchange. The conventional pebble heater apparatus generally comprises two chambers which may be disposed in substantially vertical alignment. The solid heat exchange material is introduced into the upper portion of the first chamber. That material forms a gravitating bed of solid heat exchange material which flows downwardly through the chamber in direct heat exchange with hot gaseous heat ex-

2

change material. The solid heat exchange material is heated to a high temperature in the heat exchange and is then gravitated to a second chamber in which the hot solid heat exchange material is caused to contact reactant materials in a second direct heat exchange relation, furnishing heat for the treatment or conversion of the reactant materials.

When such apparatus has been utilized in the cracking of heavy residual oils, it has been customary to introduce those oils directly onto the pebbles within the reaction chamber so as to coat the surface of the hot pebbles therein and thus vaporize a portion of the oil, converting the balance thereof to coke. During such operation, considerable splashing of the oil has been encountered upon its introduction into the reaction chamber. It has been found, however, that when such splashing occurs a tar mist is formed, which mist passes on through the pebble bed and is collected as a portion of the gaseous product from the reaction chamber. Such tar mists are very undesirable in the finished product and, therefore, it is necessary to carry out a separation of such materials from the desired product.

I have conceived a means and method whereby the formation of tar mists and its concomitant recovery as a portion of the reaction product is substantially obviated. Broadly speaking, this invention comprises heating a heavy residual oil to a temperature suitable for flashing and preferably to a temperature at least about its initial boiling point, gradually introducing the heated oil into the upper portion or flash zone of a reaction chamber which contains a plurality of baffles above the top surface of the pebble bed contained therein. The heated oil is gradually introduced into the flash zone through a perforate header and is allowed to drip onto the baffles immediately below each header, allowing the oil to be spread thereover in thin films. The oil flashes in this portion of the reaction chamber with practically no formation of tar mist. Any minute amount of tar mist which is formed is knocked down by other baffles in the flash zone. Vapors from the upper portion of the reaction chamber are passed upwardly into a vapor phase reaction chamber in which the flashed vapors are converted to high purity olefins. Liquid which drains from the surface of the plurality of baffles within the upper portion of the reaction chamber gravitates onto the surface of pebbles within the pebble bed. A portion of the liquid material is converted by the heat exchange with the hot pebbles and forms a gaseous effluent which is collected in

the upper portion of the pebble bed and is removed therefrom as a desired product of the reaction. The unvaporized oil is converted to coke in and on the surface of the pebbles. With sufficiently porous pebbles the tar is sufficiently removed from contactable points on the periphery of the pebbles that a tendency for the pebbles to stick together and cluster is substantially obviated. The coke is subsequently oxidized for the purpose of heating the pebbles so as to provide necessary heat for the conversion of the residual oils.

Solid heat exchange material which may be utilized in the pebble heater system of this invention is generally termed "pebbles." The term "pebbles" as used herein denotes any substantially solid material of flowable size and form which has sufficient strength to withstand mechanical pressures and the temperatures encountered within the pebble heater system. These pebbles must be of such structure that they can carry large amounts of heat from one chamber to another without rapid deterioration or substantial breakage. Pebbles which may be satisfactorily used in this oil conversion system may be substantially spherical in shape and range from about one-eighth inch to about one inch in diameter. The pebbles are preferably of a size within the range of from one-eighth inch to five eighths inch in diameter. Materials which may be used single or in combination in the formation of such pebbles include among others alumina, silicon carbide, periclase, beryllia, mullite, nickel, cobalt, copper, iron, magnesia, and silica. It is preferred that the pebbles be very porous, similar in structure to a sponge.

Pebbles which are preferred for the operation of the process described herein are very porous pebbles which can hold relatively large amounts of carbon without forming pebble clusters. These pebbles are preferably formed from the material described above, but are prepared by a particular process of pebble manufacture. During the mixing stage of the pebble, a material is added there to such as fine particles of coke, ammonium chloride, or ammonium carbonate. Such fine materials when removed from the pebbles result in a desired pore size, the fine materials being controlled as to size before incorporation in the pebble mass. The water content of the pebble mixture is controlled within the range of between 12 per cent and 18 per cent by weight and after the pebbles have been extruded or cut into small pieces they are rolled in a ball mill or are tumbled in a zone containing additional small particles of coke, ammonium chloride, or ammonium carbonate in such a manner that the small particles are caused to be imbedded in the surface of the pebbles. After the small particles are decomposed during heating the pebbles have very large pores, somewhat akin to a sponge. If rolling in a ball mill is the method utilized in the formation of the pebbles, a plate having relatively pointed teeth thereon may be utilized as one of the rolling surfaces so as to mechanically provide desired indentations in the surface of the pebbles. The pebbles are heat treated at a temperature in the neighborhood of 2500° F. so as to cause the fine particles added during mixing of the pebbles to be decomposed over a somewhat lengthy heating period. The pebbles are also hardened during such heating so as to obtain the desired properties for resistance of abrasion and fracturing.

An object of this invention is to provide an

improved method for converting heavy residual oils. Another object of the invention is to provide an improved system for cracking heavy residual oils. Another object of the invention is to provide a method for cracking heavy residual oils by heat treatment in pebble heater apparatus without a substantial formation of tar mist therein. Another object of the invention is to provide an improved pebble heater apparatus for particular use in the conversion of heavy residual oils to lower boiling products. Another object of the invention is to provide an improved method for producing pebbles. Other and further objects and advantages will be apparent to those skilled in the art upon study of the accompanying disclosure and the drawings.

More complete understanding of the invention will be obtained upon reference to the schematic drawings in which Figure 1 is a diagrammatic elevation, partly in section, of the improved pebble heater apparatus of this invention. Figure 2 is a broken section view of the upper portion of the reaction chamber of Figure 1.

Referring particularly to the device shown as Figure 1 of the drawings, pebble heater chamber 11 is an upright, elongated chamber which is closed at its upper and lower ends by closure members 12 and 13, respectively. Pebble inlet conduit 14 is provided in the upper end of pebble heater chamber 11, preferably in closure member 12. Inlet header member 15 is provided about the lower end portion of pebble heater chamber 11, preferably around closure member 13, and communicates with the interior of chamber 11 through the wall thereof. Inlet conduit 16, having flow control valve 17 therein, is connected to header member 15 as is inlet conduit 18 having flow control 19 provided therein. Gaseous effluent conduit 20 is provided in the upper portion of chamber 11, preferably in closure member 12. Vapor phase reaction chamber 21 is an upright elongated chamber being closed at its upper and lower ends by closure members 22 and 23, respectively. Pebble conduit 24 extends downwardly from closure member 13 of chamber 11 into the interior of chamber 21, preferably substantially coaxial with each chamber. It is within the scope of this invention to provide a plurality of pebble conduits between the lower portion of chamber 11 and the upper portion of chamber 21. Such pebble conduits would be disposed so as to be uniformly distributed over the outlet and inlet areas of the respective chambers. Inlet conduit 25, having flow control valve 26 provided therein, extends into pebble conduit 24 so as to provide inlet means for introduction of a sealing gas into conduit 24. Gaseous effluent outlet conduit 27 extends from the upper portion of vapor phase reaction chamber 21 to a recovery system 28. Gaseous effluent conduit 29 extends from recovery system 28 to a disposal point, not shown. Liquid effluent conduit 31 extends from recovery system 28 to a disposal point, not shown. Liquid phase reaction chamber 32 is an elongated upright chamber being closed at its upper and lower ends by closure members 33 and 34, respectively. Pebble conduit 35 extends downwardly from the lower portion of vapor phase reaction chamber 21 into the interior of reaction chamber 32. Pebble conduit 24 and pebble conduit 35 extend a substantial distance downwardly into the respective reaction chambers so as to provide considerable void spaces between their lower ends and the upper end closure members of the respective re-

action chambers. Pebble conduit 35 preferably extends coaxially with both reaction chamber 21 and reaction chamber 32.

In this specific modification of the invention, a pebble support member 36 is provided within the lower portion of vapor phase reaction chamber 21 and surrounds and supports the inlet end of pebble conduit 35. Pebble support member 36 is provided with perforations 37 uniformly distributed therethrough so as to permit the passage of gaseous materials but so as to prevent gravitation of pebbles therethrough. Gaseous effluent conduits 38 extend from the upper portion of reaction chamber 32 to the lower portion of vapor phase reaction chamber 21 at a point below pebble support member 36. Pebble support member 36 is preferably a refractory self-supporting arch which is capable of supporting a large amount of weight in addition to its own weight.

Although chamber 21 has been specifically described as containing pebble support member 36, chamber 21 may also be constructed so as to omit support member 36. In such construction pebble conduit 35 would extend downwardly from the bottom of chamber 21. A bustle ring would be constructed so as to encircle the lower portion of chamber 21 and would communicate with the interior of that chamber through the walls thereof. Conduits 38 would then be connected to the bustle ring which would form a gas distributing zone. A plurality of circular, downwardly extending baffles and circular inlet headers are provided to encircle the outlet end of pebble conduit 35. Better understanding of this system of baffles will be obtained upon reference to the description of Figure 2 hereafter. The baffles are provided with lower edges which have a saw tooth appearance. The saw tooth structure of the baffles makes possible a more uniform distribution of oil from each baffle. A perforate baffle 39 is provided a short distance below the outlet end of pebble conduit 35, preferably coaxial therewith. A ball-type inlet header 41 is provided within the upper portion of baffle 39 and is connected to inlet conduit 42 having flow control valve 43 provided therein. Outlet openings are provided in header 41 which extend downwardly parallel to the surface of baffle 39. Immediately below header 41 is a baffle member 44 which extends across a considerable portion of the horizontal cross-section of baffle 39 but is preferably coaxially positioned therein. Outlet header 45 is provided within the lower portion of the interior of baffle member 39 below baffle member 44 and is connected to outlet conduit 46 which is, in turn, connected to recovery system 47. Gaseous effluent conduit 48 extends between recovery system 47 and a disposal point, not shown. Liquid effluent conduit 49 extends between recovery system 47 and a disposal point, not shown. Header member 51 encircles at least a portion of the lower part of reaction chamber 32, preferably closure member 34, and communicates with the interior of reaction chamber 32 through the walls thereof.

Pebble outlet conduit 52 is provided in closure member 34 of reaction chamber 32 and is divided into pebble outlet conduits 53 and 54. Pebble outlet conduit 53 extends downwardly into the central portion of heater chamber 55. Inlet conduit 56 is provided within the upper portion of heater 55 and above the pebble bed therein, preferably forming a coil about pebble outlet conduit 53 within the upper portion of heater 55 and extending from heater 55 to connect with header member 51 and has flow control valve 57 provided

therein. Pebble outlet conduit 54 is connected at its lower end to the lower end portion of elevator 58. Elevator 58 is connected at its upper end portion to pebble inlet conduit 14 in pebble heater chamber 11. Elevator 58 may be a gas lift-type elevator or may be a mechanical elevator, such as a bucket elevator or a helical screw-type elevator. Pebble feeder 59 is provided intermediate the ends of pebble conduit 54 and may be any conventional type pebble feeder such as a star valve, a vibratory feeder, a gate valve, or a rotatable table-type feeder. Pebble outlet conduit 61 extends from the lower end portion of heater chamber 55 to the lower end portion of elevator 58. Conduit 61 may be inclined sufficiently to permit pebbles to gravitate therethrough or may be provided with a mechanical feeder such as a helical conveyor. Inlet conduit 62, having flow control valve 63 provided therein, extends into the lower end portion of heater chamber 55. A mechanical stoker may be provided instead of heater 55 to burn a small amount of coke from pebbles for heating steam.

Referring particularly to Figure 2 of the drawings, closure member 33 of reaction chamber 32 is preferably provided with a partial lining 64 so as to direct gaseous materials upwardly and outwardly away from pebble conduit 35 to gaseous effluent conduits 38. Header members 65 which are of different diameters are provided so as to preferably coaxially encircle the lower end portion of pebble conduit 35. Baffle members 66 also surround the lower end portion of pebble conduit 35 and extend downwardly from within the circle formed by each of the header members 65 and outwardly to a circle at least as large as the outer diameter of the circle formed by the nearest header member 65. Each baffle member 67 extends inwardly and downwardly from a circle having at least as great a diameter as that formed by the inner diameter of adjacent header member 65 which surrounds its lower end portion. Individual baffle members 67 preferably have curved cross-sections and extend into the circles formed by the upper end portions of baffle members 68. Baffle members 68 extend upwardly from within circles formed by closely encircling baffles 67 and upwardly and outwardly therefrom so as to overlap the baffles 67 which surround their lower portions. Headers 65 are connected to heater 69 by inlet conduit 71 which is divided into a plurality of branches which are provided with flow control valves therein. Header members 65 are provided with a plurality of perforations spaced about their upper sides and may also be provided with saw tooth-like extensions along their lower surfaces so as to more evenly distribute dripping of the oil introduced through the headers.

I have conceived a process which is conveniently adaptable to the operation of the specific apparatus set forth above. This process is, therefore, particularly described in connection with the specific apparatus. Pebbles are introduced into the upper portion of pebble heater chamber 11 through inlet conduit 14 and form a gravitating gas-permeous mass therein. These pebbles are preferably covered and contain in their porous structures a substantial amount of coke material. Air is introduced into chamber 11 through inlet conduit 16 and a sufficient amount of water is introduced into that chamber through conduit 18 to temper the pebble temperatures therein. Air which is introduced into pebble heater chamber 11 oxidizes the carbon carried on the surface of the pebbles and sufficient

water is introduced thereinto to control the temperature of the pebbles at between 1300° F. and 1800° F. The pebbles which are heated in this manner are gravitated from pebble heater chamber 11 through pebble conduit 24 into the upper portion of vapor phase reaction chamber 21. As pointed out above, it is desired to utilize very porous pebbles in this process.

A sealing gas, such as steam or a normally gaseous hydrocarbon, is introduced into pebble conduit 24 through inlet conduit 25. This sealing gas prevents the flow of combustion products and reaction products between pebble heater chamber 11 and vapor phase reaction chamber 21. The pebbles are introduced into vapor phase reaction chamber 21 at a temperature between about 1100° F. and 1600° F., preferably between 1150° F. and 1350° F. The pebble mass is gravitated through chamber 21 into the upper portion of reaction chamber 32 and flows downwardly over the surface of baffle member 39. The pebbles are preferably introduced into liquid phase reaction chamber 32 at a temperature between about 900° F. and 1400° F., preferably between 950° F. and 1100° F. A hydrocarbon oil having an API gravity above about 10° and preferably within the limits of between 10° and 25° is heated to a temperature suitable for flashing and preferably to a temperature at least about its initial boiling point, ordinarily to a temperature between about 300° F. and 1100° F., preferably between 750° F. and 950° F. The heated oil is introduced into the upper portion of reaction chamber 32 through inlet conduit 71 and header members 65. The oil slowly flows from perforations in header members 65 and flows downwardly over the headers and drips onto the baffles below the headers so as to cause the dispersion of the oil over the surfaces of the various baffles as a thin oil film thereon. Vapors are flashed from the oil material with substantially no formation of tar mist. Any minute amount of tar mist which may be formed solely by flashing vapor from the thin oil film is knocked down upon contact with other baffles in the upper portion of chamber 32. Unvaporized materials flow downwardly over the surfaces of the various baffles as thin films and gravitate from the saw tooth-like projections onto the surfaces and into the pores of pebbles making up the pebble mass within chamber 32. The liquid is heated by the direct heat exchange with the hot pebbles in chamber 32 and an additional portion of the oil is vaporized thereby.

Superheated steam, preferably at a temperature within the range of between 800° F. and 850° F., is introduced into the interior of the baffle member 39 through inlet conduit 42 and header member 41. The steam is ejected downwardly along the inner surface of baffle member 39 and escapes through perforations in baffle member 39 flowing upwardly through the thin layer of pebbles covering baffle member 39 facilitating vaporization of the oil. The steam is introduced into the confines of baffle member 39 at a rate of between about 1/4 pound to 1 pound of steam per pound of oil feed. This flow of steam aids in the separation of vaporous materials from the pebbles and the steam and the vaporous materials are caused to flow upwardly from chamber 32 into vapor phase reaction chamber 21. The gaseous materials are collected within that chamber below the support member 36 where good mixing thereof is obtained. The gases then flow upwardly through perforations 37 in support member 36 and through the hot pebble mass within

chamber 21. The gaseous materials are converted within vapor phase reaction chamber 21 to form olefinic materials which are recoverable in purity of about 95 per cent. Hydrogen is also formed as a product in reaction chamber 21. Reaction products obtained from vapor phase reaction 21 are removed therefrom through gaseous effluent conduit 27 to recovery system 28. Condensation of normally liquid olefinic materials is obtained within the recovery system and olefinic liquid is removed therefrom through liquid effluent conduit 31 and olefinic gaseous materials are removed therefrom through gaseous effluent conduit 29. The liquid olefins boil in a range above 80° F. depending specifically upon the severity of treatment. The liquid recovered from the separation or recovery system is at least 95 per cent olefins.

Unvaporized liquid materials on the surface of pebbles within reaction chamber 32 are subjected to additional heat treatment during which a part of the liquid material is vaporized. Material which is vaporized at a level below baffle member 39 passes upwardly into the void space below baffle 39 and is collected through header member 45 and is removed from the reaction chamber through conduit 46 to recovery system 47. Normally liquid materials are condensed in recovery system 47 and coker liquid is removed from the recovery system through liquid effluent conduit 48 while normally gaseous coker material is removed therefrom through conduit 49. The unvaporized hydrocarbon material is converted to coke in and on the pebbles and is carried downwardly through reaction chamber 32 with those pebbles. This unvaporized material constitutes tar which is maintained on the surface of the pebbles within reaction chamber 32 for a period of between 30 and 60 minutes. This contact time is sufficient to coke the tar and release any desirable gaseous product therefrom. The coke covered pebbles are removed from the bottom of chamber 32 through pebble outlet conduit 52 and a small portion of the coke covered pebbles is introduced into heater chamber 55 through pebble conduit 53. Steam is passed by means of conduit 55 through the upper portion of heater chamber 55 above the surface of the pebble bed therein. Air is introduced into the lower portion of heater 55 so as to oxidize the carbon material and release heat which is sufficient to superheat the steam passing through conduit 56, preferably to a temperature within the range of between 800° F. and 850° F. The pebbles are removed from the bottom of heater chamber 55 and are combined with the pebbles carried through pebble conduit 54 and are elevated to the upper portion of pebble heater chamber 11. The steam which is introduced into the lower portion of reaction chamber 32 through header member 51 is in an amount of about 0.1 pound or less per pound of oil. This steam is utilized only to assure positive flow of gas upwardly through the reaction chamber.

65 Better understanding of this invention will be obtained upon reference to the specific example below.

Specific example

70 An oil feed is heated to about 850° F. and is introduced onto the surface of a plurality of baffle members as thin oil films so as to prevent splashing in an oil flashing zone. The oil is flashed therein and unvaporized oil is gravitated onto the 75 surface of a gravitating mass of pebbles which is

at about 950° F. Specific properties of the oil feed, flashed vapors, and liquid oil gravitated onto the pebble mass are set forth below as Table I.

Table I

	Feed	Vapors	Gravitated Liquid Oil
API Gravity	18.5	24.1	13.9
Viscosity, Saybolt Furol @210° F.	64.8	52.4	443.0
Carbon Residue (Ramsbottom)	12.6	2.6	16.6
Pour Point, ° F.	85	120	105
B. S. & W.	0.1		0.1
Vacuum Distillation (corrected to 760 mm. Hg), ° F.:

5%	921	898	-----
10%	954	936	-----
20%	995	889	-----
30%			1,016
50%			1,048

Steam is introduced into the oil coated pebble mass a short distance below its top layer. The steam which is superheated to about 800° F. aids greatly in gently vaporizing the lighter constituents.

The vapors are passed into the lower portion of a vapor phase cracking zone and countercurrent to a gravitating mass of hot pebbles therein. Pebbles are introduced into the upper portion of the vapor phase cracking zone at about 1250° F. The vapors are cracked into predominantly olefin material. Products resulting from the reaction in the vapor phase cracking zone are passed to a recovery zone from which a gaseous fraction and a liquid fraction are obtained. The gas fraction represents about 45 weight per cent of the vaporous products fed to the recovery zone. An analysis of the gas fraction is set forth below in Table II.

Table II

Gas	Mol Percent
H ₂	13.
CH ₄	16.
Ethylene	45
Propylene	15 about 95% pure.
Butylene	11

The oil which is not stripped from the pebbles by flow of steam through the top layer of the pebble mass is slowly converted to coke in a reaction zone. Vapor which is released in the reaction zone during the coking step is removed therefrom as coker gas. Coker gas is mainly paraffinic. The coker gas is passed to a recovery zone from which a gaseous fraction and a liquid fraction are obtained. An analysis of the gas fraction is set forth below in Table III. The gas fraction represents about 15 weight per cent of the vaporous products fed to the recovery zone.

Table III

Gas:	Mol per cent
H ₂	4.2
CH ₄	29.7
C ₂ H ₄	1.2
C ₂ H ₆	23.3
C ₃ H ₆	4.1
C ₃ H ₈	19.5
C ₄ H ₈	4.6
C ₄ H ₁₀	13.4

Gasoline and gas oil form the major portion of the coker products. Of the liquid fraction, gasoline comprises about 20 weight per cent and gas oil about 80 weight per cent.

The amount of coke which is formed depends

mainly on the type of oil which is fed. Coke on the surface of pebbles may be used to supply heat for a feed preheater, a steam superheater, and the pebble heater, depending upon the amount of coke produced.

I have disclosed that the oil feed is heated to a temperature which is suitable for flashing. That temperature is not necessarily as high as the initial boiling point of the feed (STP). Flashing conditions are obtained in one respect by reducing the partial pressure of the feed oil by the introduction of steam into the flash chamber through inlet header 41 and the top of the pebble bed.

Many modifications of this invention will be apparent to those skilled in the art upon study of this disclosure. Such modifications are believed to be within the scope of the invention disclosed herein.

I claim:

1. The process of converting hydrocarbon oil which comprises the steps of heating said oil to a temperature suitable for flashing and within the range of between 300° F. and 1100° F. in a first heating zone; slowly admitting said heated oil into a flash zone at a plurality of dispersed points; gravitating said oil onto and over downwardly projecting baffles as thin films in said flash zone; flashing vapors from said gravitating oil; gravitating pebbles into a vapor phase reaction zone at a temperature within the range of between 1100° F. and 1600° F. and downwardly therethrough as a contiguous pebble mass; gravitating said pebbles through said flash zone and into a liquid phase reaction zone at a temperature within the range of between 900° F. and 1400° F. and downwardly therethrough as a contiguous pebble mass; depositing oil which drips from said baffles in said flash zone on the surface of pebbles within said liquid phase reaction zone; introducing superheated steam beneath the surface of said pebble mass in said liquid phase reaction zone at a rate of between 0.25 and 1 pound of steam per pound of oil feed; passing said steam and any vapors stripped thereby from said oil upwardly through said flash zone and with said flashed vapors from said flash zone into the lower portion of said vapor phase reaction zone; passing said vapors in direct heat exchange with and countercurrent to the flow of said pebbles in said vapor phase reaction zone so as to cause the conversion of said vapors predominantly to olefins; removing a predominantly olefin product stream from the upper portion of said vapor phase reaction zone; reacting liquid oil on the surface of said pebbles in said liquid phase reaction zone so as to convert vaporizable materials to predominantly paraffinic products and to convert non-vaporizable materials to coke on said pebbles; removing said predominantly paraffinic products from within the upper portion of said pebble mass in said liquid phase reaction zone in a gaseous form; gravitating said coke covered pebbles from said liquid phase reaction zone; oxidizing and regenerating said coke from said pebbles so as to heat same; and reintroducing said pebbles into said vapor phase reaction zone at a temperature in the range of between 1100° F. and 1600° F.

2. The process of claim 1 wherein steam at a temperature within the range of between 300° F. and 850° F. is introduced into the lower portion of said liquid phase reaction zone at a rate of up to 0.1 pound per pound of oil feed.

3. The process of claim 1 wherein said hydrocarbon oil has an API gravity above 10°.

4. The process of converting hydrocarbon oil which comprises the steps of heating an oil having an API gravity within the range of between 10° and 25° to a temperature of at least about its initial boiling point and within the range of between 750° F. and 950° F. in a first heating zone; slowly admitting said heated oil into a flash zone at a plurality of dispersed points; gravitating said oil onto and over downwardly projecting baffles substantially without splashing and as thin films in said flash zone; flashing vapors from said gravitating oil; gravitating pebbles into a vapor phase reaction zone at a temperature within the range of between 1150° F. and 1350° F. and downwardly therethrough as a contiguous pebble mass; gravitating said pebbles through the central portion of said flash zone and into a liquid phase reaction zone at a temperature within the range of between 950° F. and 1100° F. and downwardly therethrough as a contiguous pebble mass; depositing oil which drips from said baffles in said flash zone on the surface of pebbles within said liquid phase reaction zone; introducing steam at a temperature within the range of between 800° F. and 850° F. beneath a thin layer of said pebbles within said liquid phase reaction zone at a rate of between 0.25 and 1 pound of steam per pound of oil feed; passing said steam and any vapors stripped thereby from said oil upwardly through said flash zone and with said flashed vapors from said flash zone into the lower portion of said vapor phase reaction zone; passing said vapors in direct heat exchange with and countercurrent to the flow of said pebbles in said vapor phase reaction zone so as to cause the conversion of said vapors predominantly to olefins; removing predominantly olefinic product stream from the upper portion of said vapor phase reaction zone; reacting liquid oil on the surface of said pebbles in said liquid phase reaction zone so as to convert vaporizable material to predominantly paraffinic products and to convert non-vaporizable materials to coke on said pebbles; removing said predominantly paraffinic products from within the upper portion of said pebble mass in said liquid phase reaction zone in a gaseous form; gravitating said coke covered pebbles from said liquid phase reaction zone; oxidizing and regenerating said coke from said pebbles so as to heat same; and reintroducing said pebbles into said vapor phase reaction zone at a temperature in the range of between 1150° F. and 1350° F.

5. The process of claim 4 wherein steam at a temperature within the range of between 800° F. and 850° F. is introduced into the lower portion of said liquid phase reaction zone at a rate up to 0.1 pound per pound of oil feed.

6. The process of claim 4 wherein said pebbles are very porous in structure and said oil which is deposited on said pebbles in said liquid phase reaction zone is deposited on the surface and in the pores of said pebbles.

7. The process of claim 4 wherein a portion of said coke-bearing pebbles is passed to a first heater zone; a controlled amount of oxygen is introduced into the lower portion of said first heater zone so as to oxidize a portion of said coke in said heater zone; steam is passed in indirect heat exchange with oxidation products obtained by the oxidation of said coke in said

first heater zone at such a rate as to heat said steam to a temperature within the range of between 800° F. and 850° F.; introducing said steam into the bottom portion of said liquid phase reaction zone in an amount only sufficient to maintain positive gaseous upflow in said liquid phase reaction zone; removing said pebbles from the lower portion of said first heater zone and combining them with the balance of said coke-bearing pebbles from said liquid phase reaction zone and passing said pebbles to a second heating zone for oxidizing and regeneration.

8. The process of claim 7 wherein oxygen is introduced into the lower portion of said second heating zone; introducing a controlled amount of water into the lower portion of said second heating zone so as to control the pebble outlet temperature within a range of between 1300° F. and 1800° F.; gravitating said heated pebbles from said second heating zone into said vapor phase reaction zone; and removing gaseous effluent from the upper portion of said second heating zone.

9. Improved pebble heater apparatus which comprises in combination an upright elongated closed pebble heater chamber; pebble inlet means in the upper portion of said pebble heater chamber; gaseous effluent outlet means in the upper portion of said heating chamber; air inlet means in the lower portion of said heating chamber; water fog inlet means in the lower portion of said heating chamber; an upright elongated closed vapor phase reaction chamber below said heater chamber; a pebble conduit extending downwardly from the bottom of said heater chamber into the interior of said vapor phase reaction chamber; sealing gas inlet means connected to said pebble conduit between said heating chamber and said vapor phase reaction chamber; a first recovery means; gaseous effluent conduit means extending from said first recovery means; liquid effluent conduit means extending from said first recovery means; gaseous effluent outlet conduit means extending between the upper portion of said vapor phase reaction chamber and said recovery means; a perforate refractory load-supporting dome within the lower portion of said vapor phase reaction chamber dividing said vapor phase reaction chamber into a reaction zone above said dome and a distribution zone below said dome; an upright elongated closed liquid phase reaction chamber below said vapor phase reaction chamber; gaseous effluent conduits extending from the top of said liquid phase reaction zone to said vapor phase reaction zone below said perforate refractory dome; a pebble conduit extending coaxially downwardly from said refractory dome in said vapor phase reaction chamber into the interior of said liquid phase reaction chamber; a plurality of circular inlet headers of different diameters having outlet openings spaced apart in their upper surfaces provided in the upper portion of said liquid phase reaction chamber and encircling said pebble conduit therein; a first plurality of circular baffles of different diameters in the upper portion of said liquid phase reaction chamber disposed so that one said baffle member extends downwardly from within the circle formed by and adjacent each said circular header member and outwardly to a circle at least as large as the outer diameter of the circle formed by the header member immediately above; an oil heater; oil

13

conduit means extending between said oil heater and said circular header members within said liquid phase reaction chamber; a perforate conical baffle having an outer diameter somewhat smaller than the inner diameter of said liquid phase reaction chamber disposed coaxially with and a short distance below the outlet end of said pebble conduit in the upper portion of said liquid phase reaction chamber; steam inlet means within the upper portion of said perforate conical baffle and having outlet openings extending parallel to the surface of said conical baffle; steam conduit means extending through the wall of said liquid phase reaction chamber to said steam inlet means within said perforate conical baffle; outlet header means within the lower portion of said perforate conical baffle; second recovery means; gaseous effluent conduit means extending from said second recovery means; liquid effluent conduit means extending from said second recovery means; gaseous effluent conduit means extending from said outlet header in said liquid phase reaction chamber to said recovery means; a disc baffle within said perforate conical baffle in said liquid phase reaction chamber intermediate said steam inlet means and said outlet header means and being spaced from the wall of said perforate con-

14

ical baffle; pebble outlet means in the bottom of said liquid phase reaction chamber; elevator means connected at its lower end portion to said pebble outlet means from said liquid phase reaction chamber and at its upper end portion to said pebble inlet means in said heater chamber; and steam inlet means connected to the lower portion of said liquid phase reaction chamber.

5 10. Pebble heater apparatus of claim 9 wherein in a plurality of circular baffles of different diameters encircle said pebble conduit in the upper portion of said liquid phase reaction chamber and are disposed above said circular headers.

15 11. The process of claim 1 wherein said pebbles are highly porous.
